(57) **CLAIM**

The ornamental design for a cell phone rack, as shown and described.

DESCRIPTION

FIG. 1 is an isometric operational view of a cell phone rack showing my new design having three cellphones thereof; FIG. 2 is an isometric view thereof;

FIG. 3 is an exploded view thereof;

FIG. 4 is a front elevational view thereof;

FIG. 5 is a top plan view thereof;

FIG. 6 is a bottom plan view thereof;

FIG. 7 is a right elevational view thereof;

FIG. 8 is a left side elevational view thereof;

FIG. 9 is a rear elevational view thereof; and,

FIG. 10 is an isometric operational view showing my design having the rear portion in an expanded configuration and having the front portion attached thereto.

No claim is made to the cellphones shown in broken lines, it is shown for illustration purposes only.
